UNITED STATES PATENT OFFICE.

LAMBERT T. FOLLANSBEE, OF WASHINGTON, DISTRICT OF COLUMBIA.

TRAP.

SPECIFICATION forming part of Letters Patent No. 404,271, dated May 28, 1889.

Application filed August 21, 1888. Serial No. 283,300. (No model.)

To all whom it may concern:

Be it known that I, LAMBERT T. FOLLANSBEE, a citizen of the United States of America, residing at Washington, in the District of Columbia, have invented certain new and useful Improvements in Bath-Tub Traps, of which the following is a specification, reference being had therein to the accompanying drawing.

My invention relates to bath-tub traps; and 10 it has for its object to provide a trap which, in the event of its becoming fouled or choked up, can be readily and easily cleaned.

A very common type of bath-tub traps now in use is a **U** or **S** shaped lead pipe having 15 an opening in its under side at the bend, through which sediment may be drawn off, the opening being closed by a screw-plug. As the tub sits on the floor of the room, the trap must necessarily be placed under the 20 floor, which frequently gives rise to a great deal of trouble, for if the trap becomes choked a portion of the floor must be taken up in order to get access to the screw-plug and to place a vessel under the opening in the pipe 25 to catch the contents of the trap. Then again, if there should be a leak at the plugged opening, the ceiling of the room below would be injured before the leak would be discovered. These difficulties may be entirely avoided by 30 means of my invention, which I will now proceed to describe.

The accompanying drawing is a vertical sectional view of my improved trap in position.

A represents the bath-tub, a portion only 35 of which is shown.

B is the usual grated thimble leading from the interior of the tub into the mouth of the trap, and C is the stopper for the thimble.

D is the pan usually placed under the tub.

40 E E' is the trap, which is made, preferably, of lead pipe. It consists of two branches, one of which, E, is bent into **U** or other like form, while the other branch, E', is straight and intersects branch E in the under side of its 45 bend, its lower end being provided with a screw-tap, T.

When the trap is in position, one end of branch E extends upward through the floor F, upon which the bath-tub is set, and is in communication with the interior of the tub by means 50 of the ordinary grated thimble, the other end

of the bent branch being connected to the discharge-pipe G under the floor. The straight branch E' extends downward through the ceiling H of the room below far enough to 55 receive the screw-tap T, which may, if desired, be made to resemble a rosette or other like ornament.

A rod, I, carrying at its upper end a stopper, S, for closing the upper end of branch 60 E', is swiveled in the tap T, the rod being provided with a shoulder, i, which rests against the inner side of the tap, and the outer end of the rod being headed down loosely onto the tap, as clearly shown. The stopper may be 65 either rigidly or loosely secured to the rod. This construction enables the tap to be turned without turning the stopper. The stopper, on being reciprocated in branch E' after the tap is unscrewed, will serve as a piston and tend 70 to start the obstruction in the trap.

If preferred, the stopper and its carrying-rod may be dispensed with and the water in the trap allowed to fill the branch E'.

By unscrewing the tap T any obstruction 75 in the trap—such as matches, hair, and the like—can be readily removed without in the least disturbing either the floor or ceiling. As the tap is below the ceiling, no damage would result to the latter if there should be a leak 80 at the former.

Having thus described my invention, what I claim as new, and desire to secure by Letters Patent, is—

1. A bath-tub trap consisting of a **U** or other 85 suitably-bent pipe and a straight pipe communicating with the bent pipe at the under side of its bend, one end of the bent pipe passing up through the floor on which the tub sits and communicating with the interior of 90 the tub, while its other end is connected to the discharge-pipe, the straight pipe passing downward through the ceiling of the room below and provided at its lower end with a screw-tap, substantially as described. 95

2. A bath-tub trap consisting of a **U** or other suitably-bent pipe and a straight pipe communicating with the bent pipe at the under side of its bend, one end of the bent pipe passing up through the floor on which the tub sits 100 and communicating with the interior of the tub, while its other end is connected to the

discharge - pipe, the straight pipe passing downward through the ceiling of the room below and provided with a stopper for closing its upper end, a screw-tap for closing its lower 5 end, and a rod connecting the stopper and tap, whereby on unscrewing the latter the former may be withdrawn, substantially as described, and for the purposes set forth.

In testimony whereof I affix my signature in presence of two witnesses.

LAMBERT T. FOLLANSBEE.
